CLAIM

The ornamental design for a liner for adhesive film, as shown and described.

DESCRIPTION

FIG. 1 is a top perspective view of a liner for adhesive film according to our design;

FIG. 2 is a bottom perspective view thereof;

FIG. 3 is a top view thereof;

FIG. 4 is a right side elevation view thereof;

FIG. 5 is a left side elevation view thereof;

FIG. 6 is a back elevation view thereof; and,

FIG. 7 is a front elevation view thereof.

The dash-dot-dash broken lines surrounding the top of the liner for adhesive film shown in FIGS. 1 and 3 depict the boundaries of the claim and form no part thereof. Beneath the top surfaces, all broken lines and areas including the depth and bottom of the article are portions of the liner for adhesive film that are not included in the claim.
